DRAPE FIXTURE

Lewis M. Dixon, Sea Cliff, N. Y.

Application September 18, 1945, Serial No. 617,092

6 Claims. (Cl. 160—341)

1

This invention relates to curtains, drapes, portieres and the like, and more particularly to operating means for the same, whereby they may be drawn closed, or opened.

The invention is concerned especially with curtain or drape fixtures wherein there is a horizontal bar or rod, slidably carrying a plurality of hangers to which the curtain material is attached, the latter being supported so as to hang from the rod. Various devices have been proposed in the past for operating such curtains to draw or open the same, these devices including pull cords and pulleys, and also comparatively rigid operating poles or strips which are secured to the hangers, and hang pendant therefrom within reach of a person on the floor. These devices have involved special fittings, some of which at times get out of order or do not operate smoothly, all of the fittings generally complicating the curtain structure and increasing the cost of same substantially.

An object of the present invention is to obviate these disadvantages and drawbacks of prior devices. This is accomplished by the provision, in a curtain or drape, of an improved, trouble-free, simple and economically producable operating means whereby the drape may be conveniently drawn closed, or opened. This operating means may be provided in combination with a set of drapes, or may be provided separately as an attachment, to be quickly conveniently incorporated in existing drapes, in either case its operation being extremely simple, and troubleproof over an extended period of time.

In the specific embodiment of the invention illustrated herein as exemplary thereof the drape operating means comprises an extremely simple two-part structure comprising an apertured block adapted to be slidably carried on the drape rod, and an elongate handle secured to the block and hanging pendant therefrom within easy reach of a person standing on the floor. The aperture or bore of the block which receives the drape rod has sufficient length to prevent the block from canting or binding on the rod, yet the overall size of the block is small enough so that it may be carried between a pair of adjacent or adjoining hangers. Preferably the handle is pivotally connected to the block, so that during its operation the possibility of binding of the block is further minimized.

According to the invention the operating means comprising the block and handle may be mounted in back of a drape at the leading edge thereof so as to be invisible to occupants of a

2

room and yet be conveniently accessible for use. No change is necessary in the hangers or rod of the drape, or in the drape itself, and therefore the cost of incorporating the operating means with a set of drapes is kept to a minimum. Also, the installation of the operating means in an existing set of drapes is thereby simplified and made convenient.

Other features and advantages will hereinafter appear.

In the accompanying drawings:

Figure 1 is a front elevation of a set of drapes having incorporated the operating means of the invention.

Fig. 2 is an enlarged detail showing one drape operating means in fragmentary rear elevation, as installed, and

Fig. 3 is a fragmentary side elevation of the installed operating means.

Referring to the figures, the drape assembly and operating means of this invention comprises a horizontal rod 10 which may be mounted in any suitable manner on the framework 11 of a window 12. Slidably carried on the rod 10 are rings 13 or hangers 13 to which the drape material 14 is secured, as by sewing at spaced intervals.

According to the invention individual, novel operating means 15, identical with each other, are provided for each of the drapes 14, each of 30 said means comprising a block 16 having an aperture or opening 17 to slidably receive the rod 10. The blocks 16 may have any suitable shape, however, as shown they are substantially cylindrical, with their upper sides flattened at 18, as seen in Figs. 2 and 3. The flats 18 of the blocks extend generally parallel with the axes of the apertures 17, and the sizes of the blocks 16 are such that they may be carried on the rod 10 each between a different pair of adjoining hangers 13, preferably to extend in close proximity to the latter.

As shown in Fig. 3, the aperture 17 of the block 16 is slightly larger than the diameter of the rod 10, so that the block may slide easily on the rod. Due to the lengths of the apertures 17 in the blocks, the latter cannot cant or tilt to any substantial degree and bind on the rod 10.

For the purpose of conveniently sliding the blocks 16 along the rod 10 to either close or open the drapes, elongate handles 19 are provided, extending downwardly from the blocks to within reach of a person on the floor. The handles 19 may be secured to the blocks 16 in any suitable manner, either rigidly or flexibly, but 55 preferably they are pivotally secured so that the

possibility of binding of the blocks is further minimized when they are being operated.

In accomplishing this the blocks 16 are provided with slots 20 and the upper ends of the handles 19 with flats 21, so that the said ends may be loosely received in the slots. The blocks 16 and the upper ends of the handles 19 are provided with aligned apertures to receive pivot pins 22 by which the handles are pivotally secured to the blocks.

The blocks 16 and handles 19 may be of any suitable material such as wood or plastic, which may be economically fabricated in large quantities.

To insure easy sliding of the blocks on the rod 10, the apertures 17 are made with smooth surfaces, and if wood is employed for the material of the blocks, the walls of the apertures 17 may be waxed or otherwise treated to enable them to slide easily on the drape rod.

Referring to Fig. 1, the blocks 16 may be carried by the rod 10 between adjoining pairs of hangers 13 located adjacent the inner edges of the drapes 14. When so mounted the blocks 16 and handles 19 are normally hidden from view by the drapes 14, yet are readily accessible for use. The blocks and handles may have a color similar to that of the rod and drapes respectively, so that they blend with the same and are not readily distinguishable from the outside of the window.

In operation, to draw back the drapes the handles 19 are merely grasped at their lower ends and manipulated to move the blocks 16 toward the sides of the window. This will cause the hangers and drapes to likewise move aside, the latter becoming folded as the hangers are brought together. In a similar manner, the drapes may be extended or drawn over the window.

It will thus be seen that the present invention provides an extremely simple and foolproof operating means for drapes and the like, which does not require modification of the drape rod 10, hangers 13 or of the drape material 14. This is an extremely advantageous feature, since it enables the operating means to be incorporated in sets of drapes at extremely low cost, and also enables the operating means to be distributed as an attachment for existing drapes. An attachment such as this is extremely easy and convenient to install, since it is merely necessary to mount the blocks in the proper places on the drape rods between adjoining end hangers.

Variations and modification may be made within the scope of this invention and portions of the improvements may be used without others.

I claim:

1. For use with a drape fixture having a horizontal rod and drape material suspended by hangers slideable on said rod, a member apertured to slidably receive and be carried by the rod, said member being positioned between adjacent hangers, the extent of engagement of said member on the rod preventing its canting and binding on the rod; and an elongate handle secured to the member for extending from the latter to within reach of a person on the floor whereby the member may be slid along the rod to move the hangers and drape material carried thereby.

2. For use with a drape fixture having a horizontal rod and drape material suspended by hangers slideable on said rod, a substantially flat

member having an aperture extending between opposite end faces for slidably receiving the rod, the width of the member between said faces preventing canting and binding on the rod, and the member being carried by the rod between a pair of adjoining hangers; and an elongate handle secured to the member for extending from the latter to within reach of a person on the floor whereby the member may be slid along the drape rod to move the hangers and drape material carried thereby.

3. For use with a drape fixture having a horizontal rod and drape material suspended by hangers slideable on said rod, a block having an aperture for slidably receiving the rod, said block being adapted to be carried by the rod between a pair of adjoining hangers; and an elongate handle secured to the block, for extending from the latter to within reach of a person on the floor whereby the block may be slid along the curtain rod to move the hangers and drape material carried thereby.

4. For use with a drape fixture having a horizontal rod and drape material suspended by han-

25 gers slideable on said rod, a collar having a bore for slidably receiving the rod, said collar being adapted to be carried by the rod between a pair of adjoining hangers, and the bore being elongate to prevent canting and binding of the collar on the rod; and an elongate handle secured to the collar for extending laterally from the latter to within reach of a person on the floor whereby the collar may be slid along the drape rod to move the hangers and drape material carried thereby.

30 5. For use with a drape fixture having a horizontal rod and drape material suspended by han- 40 gers slideable on said rod, a block having a slot in one face, and having an opening extending through it for slidably receiving the rod, said block being adapted to be carried by the rod between a pair of adjoining hangers; an elongate handle adapted at one end to fit into the slot of the block, said end and block having aligned apertures; and a pin extending through the aligned apertures of the block and handle to pivotally connect the same together, the handle extending from the block to within reach of a person on the floor whereby the block may be slid along the drape rod to move the hangers and drape material carried thereby.

45 6. In a drape fixture having a horizontal rod and drape material suspended by hangers slideable on said rod, the combination with a pair 55 of adjoining hangers adjacent the edge of the drape of an apertured block slidably carried by the rod and extending between the adjoining hangers; and an elongate handle pivotally connected to the block and extending to within reach 60 of a person on the floor whereby the block may be slid along the drape rod to move the hangers and drape material carried thereby.
